UNITED STATES PATENT OFFICE.

CLARE B. FITZPATRICK, OF ADAMS PARK, GEORGIA.

SPIKE.

1,369,798.

Specification of Letters Patent.

Patented Mar. 1, 1921.

Application filed May 8, 1917. Serial No. 167,248.

To all whom it may concern:

Be it known that I, CLARE B. FITZPATRICK, a citizen of the United States, residing at Adams Park, in the county of Twiggs 5 and State of Georgia, have invented certain new and useful Improvements in Spikes; and I do hereby declare the following to be a full, clear, and exact description of the invention, such as will enable others skilled in 10 the art to which it appertains to make and use the same.

This invention relates to rail spikes, and the object of the invention is the provision of a double headed reversible spike, the 15 heads being arranged, respectively, on opposite sides of the shank of the spike and lie in planes one above the other, the said heads being identical in construction and either being adapted to engage the base flange of a 20 rail, the lowermost head being adapted to engage a rail tie when the uppermost head is engaging over the base flange of the rail so as to brace the upper end of the spike against strain.

25 Other objects will appear and be better understood from the embodiment of my invention of which the following is a specification, reference being had to the accompanying drawing forming a part thereof, 30 in which:

Figure 1 is a longitudinal sectional detail view, taken through a rail tie with a rail thereon, showing a pair of spikes, constructed in accordance with my invention, 35 and arranged in operative position.

Fig. 2 is a detail longitudinal sectional view taken through the rail tie and showing the rail in transverse section and with the lowermost heads of the spikes in engagement with the base flange of the rail, and 40

Fig. 3 is a side elevation of one of the spikes detached from operative position.

Referring to the drawing in detail, the numeral 1 designates, as an entirety, the improved spike, which is adapted to have the shank thereof driven into a rail tie A, in the ordinary manner, and the letter B designates a rail resting on the tie and adapted to be secured to the tie by means of a spike 1.

50 As shown in the drawing, the shank of the spike is provided at the upper end there-

of with a pair of oppositely extending heads, designated, respectively, by the numerals 2 and 3, the heads being identical in construction, and of the same length and located, respectively, on opposite sides of the shank. The upper head 2 is formed on the upper extremity or terminal of the shank, and the head 3 is spaced below the upper terminal of the shank and lies in a plane below that of the head 2.

The initial position of the spike is preferably that shown in Fig. 1, where the upper head 2 engages the base flange of the rail and the lower head 3 lies in engagement with the upper side of the tie. In this position the lower head 3 serves as a brace for bracing the upper end of the spike against strain exerted thereon by the rail. If the base flange of the rail happens to cut the head 2, thereby rendering the head unserviceable, the spike can be withdrawn and reversed, so as to engage the lower head 3 against the base flange of the rail.

As indicated in Fig. 1, the underside of the heads 2 and 3 are inclined outwardly and upwardly from the shank for forming a wedge.

It is evident that various changes might be resorted to in the form and construction of the spike without departing from the spirit and scope of the invention as claimed.

Having thus described my invention what I claim as new, is:

As an article of manufacture, a reversible rail spike including a shank tapered upon opposite sides and terminating in a cutting edge at the lower end of the shank, said shank having its upper end extended in opposite directions to provide offset heads of identical form, each head being provided with an upwardly and outwardly beveled rail base engaging portion and a rounded upper face, whereby the spike may be readily reversed upon damage to either head.

95 In testimony whereof I affix my signature in presence of two witnesses.

CLARE B. FITZPATRICK.

Witnesses:

W. C. HENDRICKS,
M. W. FITZPATRICK.
